RAILWAY TRACK SWITCH CONTROLLING APPARATUS

George R. Pfasterer, Greenville, Pa., assignor to
The Union Switch & Signal Company, Swiss-
vale, Pa., a corporation of Pennsylvania

Application October 19, 1938, Serial No. 235,825

7 Claims. (Cl. 246—219)

My invention relates to railway track switch controlling apparatus, and particularly to means for safeguarding the operation of a remotely controlled power operated track switch under conditions where local operation of the switch is required:

I shall describe two forms of apparatus embodying my invention, and shall then point out the novel features thereof in claims.

10 In the accompanying drawing, Fig. 1 is a diagrammatic view showing one form of apparatus embodying my invention. Fig. 2 is a diagrammatic view showing a modified form of the apparatus shown in Fig. 1, and also embodying my invention.

Similar reference characters refer to similar parts in each of the two views.

Referring first to Fig. 1, the reference character W designates a railway track switch which is operated by the well-known dual selector type of mechanism. As herein shown, this mechanism is provided with a dual selector lever S which operates a link L. When lever S is in its normal position, as shown in the drawing, link L conditions the switch W for operation by a power switch operating mechanism SM, and when lever S is in its reverse position, link L conditions the switch for operation by a manually operable lever H. The lever S is provided with a contact 2—3 which is closed only when the lever is in its normal position and the switch W is operatively connected with mechanism SM for power operation, and with a contact 2—24, closed only when the switch is conditioned for hand operation.

The power switch operating mechanism SM may take different forms, and, as shown, is of the well-known electro-pneumatic type. The mechanism SM as shown is provided with a normal valve magnet NV, a reverse valve magnet RV and a lock valve magnet LV, it being understood that when switch W is conditioned for operation by mechanism SM, the switch W will be moved to a normal position when valve magnet NV is energized and to a reverse position when valve magnet RV is energized, provided that in each instance valve magnet LV is also energized.

The reference character J designates a pole changer operatively connected, in accordance with the usual practice, with the switch W and the switch mechanism SM. As shown, pole changer J comprises contact members 14, 17 and 27, which engage normal contacts 15, 16 and 29, respectively, to form the contacts 14—15,

17—16 and 27—29 when the switch is in its normal position, but which engage reverse contacts 18, 19 and 28, respectively, to form the contacts 14—18, 17—19 and 27—28 when the switch is in its reverse position.

The reference character WR designates a polarized switch control relay. Relay WR is controlled to a normal position or to a reverse position by means of a manually operable lever L which may, for example, be a switch lever of an interlocking machine.

The reference character KR designates an indication relay which, as will be explained in detail hereinafter, is energized when and only when the position of the switch control relay WR agrees with the position of the switch W.

The reference character LR designates a normally deenergized locking relay having a first winding 25 and a second winding 26.

The operation of the apparatus of Fig. 1 will best be understood by explaining the operation and tracing the circuits simultaneously.

I shall first assume that the apparatus is in its normal condition, as shown in Fig. 1. In this condition of the apparatus, the valve magnet NV and the relays WR and KR are energized, and the relay LR and the valve magnets LV and NV are deenergized. Relay WR is energized over a normal circuit passing from terminal B of a suitable source of current, such as a battery not shown, through contact 4—5 of lever L, the winding of relay WR and contact 7—8 of lever L to terminal C of the source of current, and polar contact members 9 and 14 of relay WR are operated to their normal, or left-hand position, as viewed in Fig. 1, thereby engaging normal polar contacts 10 and 13, respectively. Relay KR is energized over a normal indication circuit passing from terminal B through contact 14—15 of pole changer J, the winding of relay KR, normal polar contact 9—10 of relay WR, contact 16—17 of pole changer J, and selector lever contact 3—2 to terminal C. Normal valve magnet NV is energized by virtue of a circuit which may be traced from terminal B through back contact 20 of relay LR, normal polar contact 11—13 of relay WR, the winding of normal magnet NV and selector lever contact 3—2 to terminal C.

With the apparatus in the normal condition, the operator may move the switch W to its reverse position. To do this, the lever L is moved to its reverse position, thereby opening the normal circuit for relay WR and establishing a reverse circuit which may be traced from ter-

- 5 minal B through contact 4-21 of lever L, the winding of relay WR and contact 22-6 of lever L to terminal C, whereby relay WR is energized in a reverse direction to swing its polar contact members 9 and 11 to the right-hand position.
- 10 The opening of normal polar contact 9-10 of relay WR opens the normal circuit for relay KR with the result that relay KR releases, thereby completing the circuit for lock valve magnet LV, this latter circuit passing from terminal B through back contact 23 of relay KR, the winding 25 of relay LR, the winding of magnet LV and selector lever contact 3-2 to terminal C. The winding 25 of relay LR and the 15 winding of magnet LV are preferably so proportioned that the flux created in magnet LV is sufficient to effectively energize that magnet valve to its open position, but the flux created by winding 25 of relay LR is insufficient to pick up the relay. The mechanism SM now operates switch W to its reverse position, because valve magnet RV is energized by virtue of a circuit passing from terminal B through back contact 20 of relay LR, reverse polar contact 25 11-12 of relay WR, the winding of magnet RV and selector lever contact 3-2 to terminal C. When the switch reaches its reverse position, relay KR is energized over a reverse indication circuit passing from terminal B through contact 30 14-18 of pole changer J, reverse polar contact 8-9 of relay WR, the winding of relay KR, contact 19-17 of pole changer J and selector lever contact 3-2 to terminal C. The energization of relay KR opens back contact 23 and thereby opens the energizing circuit for valve magnet LV, with the result that magnet LV becomes deenergized to lock the switch W and switch mechanism SM in their reverse positions.
- 35 With the switch operated to its reverse position in a manner just described, the switch may be restored to its normal position by moving the lever L to its normal position. The operation of the apparatus of Fig. 1 in this event is substantially the reverse of the operation just described, and it is believed, therefore, that this latter operation will be apparent from the foregoing description together with an inspection of the drawing without further detailed explanation.
- 40 When switch W is to be operated by hand throw lever H, it is desirable that lever L be removed from control of mechanism SM and that control of the mechanism by the lever should not be restored unless the position of the switch when conditioned for power operation by the selector lever agrees with the position of the control lever L.
- 45 Assuming that the apparatus is again in its normal condition, the movement of the selector lever S to the hand operation position disconnects the switch from the mechanism SM, operatively connects the switch with hand throw lever H, opens selector lever contact 3-2 and closes selector lever contact 24-2. The opening 50 of selector lever contact 3-2 opens the normal circuit for relay KR, whereupon relay KR releases to close back contact 23 and thereby establish a pick-up circuit for relay LR, the circuit passing from terminal B through back contact 55 23 of relay KR, winding 25 of relay LR and selector lever contact 24-2 to terminal C. Since winding 25 is not connected in series with the winding of magnet LV, relay LR picks up and completes a stick circuit for itself, this stick circuit including back contact 23 of relay KR, front

5 contact 30 of relay LR and the winding 26 of relay LR. It should be noted that the energizing circuit for lock valve magnet LV is opened at selector lever contact 3-2, and the circuits for magnets NV and RV are open at back contact 5 20 of relay LR, with the result that control of mechanism SM cannot be effected by lever L. When switch W is operated to its reverse position by means of the lever H, the contacts of pole changer J assume their reverse position. 10 Should the selector lever S be now restored to its normal or power operating position while the switch is in its reverse position, relay KR is not energized since the position of switch W is not in agreement with the position of lever L, and 15 relay LR remains energized. Lock magnet LV now becomes energized over its previously traced circuit, and reverse valve magnet RV is energized over a circuit passing from terminal B through front contact 31 of relay LR, contact 20 27-28 of pole changer J, the winding of magnet RV, and selector lever contact 3-2 to terminal C. It can be seen, therefore, that the switch is maintained in its reverse position by virtue of the power operated mechanism SM. 25

It follows that, since relay KR is energized only in the event that the position of the switch agrees with the position of the remote control lever L, and relay KR deenergized completes the stick circuit for locking relay LR, the restoration of the selector lever S to its power operating position after the switch has been hand operated into a position in disagreement with the lever L, does not result in the deenergization of relay LR. Since relay LR controls, at back 30 contact 20, the operating circuits normally governed by lever L acting through the relay WR, it is apparent that relay LR in its energized condition prevents the power operating mechanism SM from operating to move switch W into 35 agreement with the position of the control lever L.

The operator may regain control of the switch by moving lever L into agreement with the position of the switch. When lever L is moved to 45 its reverse position, the previously traced reverse circuit is completed for relay WR, whereupon relay WR is energized in its reverse direction, thereby swinging its polar contact members to the right to close the reverse polar contacts 8-9 and 50 11-12. The closing of the reverse polar contact 8-9 completes the previously traced reverse circuit for relay KR, with the result that relay KR picks up to open the stick circuit for relay LR and to open the energizing circuit for 55 valve magnet LV. Relay LR releases, thereby closing back contact 20 to complete the first traced energizing circuit for valve magnet RV, this circuit including reverse polar contact 11-12 of relay WR. The operator may now restore the 60 switch W to its normal position by restoring lever L to its normal position, as was explained hereinbefore.

Referring now to Fig. 2, the apparatus as shown is similar to the apparatus shown in Fig. 1 65 except that relay LR is now normally energized, and winding 25 of relay LR is rendered slightly slow releasing, this characteristic being effected, as shown, by connecting an asymmetrical unit 32 across the winding 25, the unit being arranged 70 to present its non-conductor direction in opposition to the flow of current in the pick-up circuit for relay LR. Also, valve magnets NV and RV are shown provided with toggle action contacts 33-34 and 35-36, respectively, of the usual type. 75

the contacts each being closed when its associated valve magnet is energized, and remaining closed until the other valve magnet is energized.

I shall describe the operation of the apparatus of Fig. 2 and shall at the same time trace the control circuits therefore. Normally, the apparatus is in the condition illustrated in Fig. 2, wherein the valve magnet NV and the relays WR, KR and LR are energized. Relay WR is energized over a simple normal circuit governed by the pole changing contacts of lever L, as was explained in detail in connection with Fig. 1, and relay KR is energized by a normal indication circuit passing from terminal B through contact 15-14 of pole changer J, the winding of relay KR, normal polar contact 9-10 of relay WR, contact 27-28 of pole changer J, normal valve magnet contact 33-34, and selector lever contact 3-2 to terminal C. Relay LR is energized over a simple pick-up circuit including front contact 37 of relay KR and the winding 25 of relay LR. The energizing circuit for valve magnet NV may be traced from terminal B through front contact 34 of relay LR, normal polar contact 11-13 of relay WR, the winding of magnet NV and selector lever contact 3-2 to terminal C.

The switch W may be operated to its reverse position by moving the lever L to its reverse position, thereby reversing the polarity of the current supplied to relay WR, which operates to its reverse position to open the normal circuit for relay KR and to prepare a circuit for magnet RV. Relay KR releases to open front contact 37, thereby opening the pick-up circuit for relay LR, and to close back contact 23. Winding 25 of relay LR, being slow-releasing, maintains front contact 30 of relay LR closed until back contact 23 of relay KR is closed, with the result that a stick circuit for relay LR is completed and which circuit also serves to energize magnet LV. This circuit passes from terminal B through back contact 23 of relay KR, front contact 20 of relay LR, winding 26 of relay LR, the winding of lock valve magnet LV, and selector lever contact 3-2 to terminal C. Lock magnet LV being energized, the switch mechanism SM actuates the switch W to its reverse position, because the reverse valve magnet RV is now energized over a circuit passing from terminal B through front contact 34 of relay LR, reverse polar contact 11-12 of relay WR, the winding of valve magnet RV and selector lever contact 3-2 to terminal C. When switch W reaches its reverse position, pole changer J is operated to its reverse position with the result that relay KR is energized over a reverse indication circuit passing from terminal B through contact 19-17 of pole changer J, reverse polar contact 8-9 of relay WR, the winding of relay KR, contact 14-18 of pole changer J, reverse valve magnet contact 35-36 and selector lever contact 3-2 to terminal C.

With the apparatus in its reverse condition, the switch may be restored to its normal condition by moving the lever L to its normal position. The operation of the apparatus in this event being substantially the reverse of the operation just described, it is believed that this latter operation will be apparent from the foregoing description together with an inspection of Fig. 2 without further detailed explanation.

When it is desired to hand operate the switch W, the selector lever S is moved from its normal, or power operating, position into its hand operating position. Assuming that the apparatus of

Fig. 2 is again in its normal condition, as shown in Fig. 2, the movement of lever S opens selector lever contact 3-2, thereby opening the circuit for normal magnet NV, and opening the normal circuit for relay KR, with the result that relay KR releases. The release of relay KR opens the energizing circuit for winding 25 of relay LR, and since the energizing circuit for winding 26 and lock valve magnet LV is open at selector lever contact 3-2, relay LR also releases. Lock valve magnet LV and relay LR being deenergized, lever L is removed from control of switch W, which may be hand operated to its reverse position by hand throw lever H. When the switch reaches its reverse position, pole changer J is operated to its reverse position, but relay KR remains deenergized since its reverse indication circuit is open at reverse polar contact 8-9 of relay WR as well as at contact 3-2. With relay KR deenergized, the restoration of selector lever S to its power operating position to close contact 3-2 while the switch is in its reverse position in disagreement with lever L, does not result in relay LR energizing. Reverse valve magnet RV of switch mechanism SM is energized, however, over a circuit passing from terminal B through contact 19-17 of pole changer J, back contact 39 of relay LR, the winding of valve magnet RV and selector lever contact 3-2 to terminal C, with the result that toggle contact 33-34 is opened, and toggle contact 35-36 is closed. Lock valve magnet LV is likewise energized over a circuit passing from terminal B through back contact 23 of relay KR, back contact 40 of relay LR, winding of valve magnet LV, and selector lever contact 3-2 to terminal C. It follows that mechanism SM acts to retain the switch at its reverse position as long as this disagreement between the switch and lever L exists. Furthermore, it is apparent that as long as locking relay LR is deenergized, the operating circuits whereby lever L normally controls the operation of mechanism SM are open at front contact 34 of the LR relay, so that mechanism SM is prevented from operating to move the switch into agreement with the position of the remote control lever L.

The operator may regain control of switch mechanism SM by moving the lever L into agreement with switch W. When lever L is moved to its reverse position, relay WR is energized over its reverse circuit to swing its polar contact members to their reverse position, whereupon relay KR becomes energized over its reverse circuit including reverse polar contact 8-9 of relay WR. The energization of relay KR closes front contact 37, whereupon winding 25 of relay LR is energized and relay LR picks up to close front contact 34 and thereby complete the first traced circuit for reverse valve magnet RV which includes reverse polar contact 11-12 of relay WR. The operator may now restore switch W to its normal position by moving lever L to its normal position, as was explained hereinbefore.

From the foregoing description of the operation of the apparatus of Figs. 1 and 2, it is apparent that I have provided simple and safe means for preventing remote control of the switch mechanism while the switch is hand operated, and also for preventing remote control unless the position of the control lever agrees with the position of the switch.

Although I have herein shown and described only two forms of apparatus embodying my invention, it is understood that various changes

and modifications may be made therein within the scope of the appended claims without departing from the spirit and scope of my invention.

Having thus described my invention, what I claim is:

1. In combination, a railway track switch, a manually controlled contact member having a normal and a reverse position, power operating means controlled by said contact member for operating said switch to its normal position in agreement with the normal position of said member and to its reverse position in agreement with the reverse position of said member, means for at times manually operating said switch, a selector lever having a normal position in which said switch is operatively connected with said power operating means and a reverse position in which said switch is operatively connected with said manual operating means, an indication relay, circuit means effective for energizing said indication relay when and only when said selector lever is in its normal position and the position of said manually controlled member agrees with the position of said switch, a normally deenergized locking relay, circuit means for energizing said locking relay governed by said indication relay, and means governed by said locking relay when energized for preventing said power operating means from operating said switch into agreement with the position of said manually controlled member.
2. In combination, a railway track switch, a control relay having a normal and a reverse position, power operating means for operating said switch to its normal position in agreement with the normal position of said manually controlled relay and to its reverse position in agreement with the reverse position of said manually controlled relay, means for at times manually operating said switch, a selector lever operable to a normal position in which said switch is operatively connected with said power operating means and to a reverse position in which said switch is operatively connected with said manual operating means, an indication relay, circuit means effective for energizing said indication relay when and only when said selector lever is in its normal position and the position of said manually controlled relay agrees with the position of said switch, a locking relay, a pick-up circuit for said locking relay governed jointly by said indication relay and said selector lever, a stick circuit for said locking relay governed by said indication relay, and means governed by said locking relay for preventing said power operating means from operating said switch into agreement with the position of said control relay.
3. In combination, a railway track switch, a control relay having a normal and a reverse position, power operating means for operating said switch to its normal position in agreement with the normal position of said control relay and to its reverse position in agreement with the reverse position of said control relay, means for at times manually operating said switch, a selector lever operable to a normal position in which said switch is operatively associated with said power operating means and to a reverse position in which said switch is operatively connected with said manual operating means, an indication relay, circuit means effective for energizing said indication relay when and only when said selector lever is in its normal position and the position of said control relay agrees with the position of said switch, a locking relay, a pick-up circuit for said

locking relay governed by said indication relay, a stick circuit for said locking relay governed jointly by said indication relay and said selector lever, and means governed by said locking relay for preventing said power operating means from operating said switch into agreement with the position of said control relay.

4. In combination, a railway track switch, a control relay having a normal and a reverse position, power operating means for operating said switch to its normal position in agreement with the normal position of said control relay and to its reverse position in agreement with the reverse position of said control relay, means for at times manually operating said switch, a selector lever having a normal position in which said switch is conditioned for operation by said power operating means and a reverse position in which said switch is conditioned for operation by said manual operating means, an indication relay, circuit means effective for energizing said indication relay when and only when said selector lever is in its normal position and the position of said control relay agrees with the position of said switch, a locking relay having a first winding and a second winding, circuit means for energizing said first winding of said locking relay governed by a front contact of said indication relay; circuit means for energizing said second winding of said locking relay governed jointly by a back contact of said indication relay, a front contact of said locking relay and a contact closed only when said switch is conditioned for operation by said power operating means; and means governed by said locking relay when deenergized for preventing said power operating means from operating the switch into agreement with the position of said control relay.

5. In combination, a railway track switch, a control relay having a normal and a reverse position, power operating means for operating said switch to its normal position in agreement with the normal position of said control relay and to its reverse position in agreement with the reverse position of said control relay, means for at times manually operating said switch, a selector lever having a normal position in which said switch is conditioned for operation by said power operating means and a reverse position in which said switch is conditioned for operation by said manual operating means, an indication relay, circuit means effective for energizing said indication relay when and only when said selector lever is in its normal position and the position of said control relay agrees with the position of said switch, a locking relay having a first winding and a second winding, circuit means for energizing said first winding of said locking relay governed jointly by a back contact of said indication relay and a contact closed only when the switch is conditioned for operation by said power operating means, circuit means governed jointly by a back contact of said indication relay and a front contact of said locking relay for energizing said second winding of said locking relay, and means governed by said locking relay when energized for preventing said power operating means from operating the switch into agreement with the position of said control relay.

6. The combination with a two position manually controlled switch relay and a railway switch having a two position selector lever effective in but one position to condition the switch for power operation, and an indication relay controlled by the switch and the switch relay and arranged to

be energized when and only when the switch is conditioned for power operation and the switch relay agrees in position with the switch, of a lock relay having a pick-up circuit and a stick circuit each of which includes a contact of the indication relay but only a selected one of which includes also a contact controlled by the selector lever and closed only in a particular one of its positions, and power operating means controlled 5 by said lock relay for moving the switch to a position of correspondence with the switch relay.

7. The combination with a two position manually controlled switch relay and a railway switch having a two-position selector lever effective in 10 but one of its two positions to condition the switch for power operation, and an indication relay con-

trolled by the switch and the switch relay and arranged to be energized when and only when the switch is conditioned for power operation and the switch relay agrees in position with the switch, of a lock relay having a pick-up winding 5 and a stick winding, a circuit for one of said windings of said lock relay including a contact of said indication relay and a contact controlled by the selector lever and closed only in a particular one of its positions, a circuit for the other of said 10 windings of said lock relay including a contact of said indication relay, and power operating means controlled by said lock relay for moving the switch to a position of correspondence with the switch relay. 15

GEORGE R. PFLASTERER.

CERTIFICATE OF CORRECTION.

Patent No. 2,184,566.

December 26, 1939.

GEORGE R. PFLASTERER.

It is hereby certified that error appears in the printed specification of the above numbered patent requiring correction as follows: Page 4, second column, line 54, claim 5, before "the" insert and; and that the said Letters Patent should be read with this correction therein that the same may conform to the record of the case in the Patent Office.

Signed and sealed this 30th day of January, A. D. 1930.

(Seal)

Henry Van Arsdale,
Acting Commissioner of Patents.
